UNITED STATES PATENT OFFICE.

GARDNER A. BELKNAP, OF CONNEAUTVILLE, PENNSYLVANIA.

RAILROAD-TIE.

No. 818,840.

Specification of Letters Patent.

Patented May 8, 1906.

Application filed January 3, 1906. Serial No. 294,437.

To all whom it may concern:

Be it known that I, GARDNER A. BELKNAP, a citizen of the United States, residing at Conneautville, in the county of Crawford and

5 State of Pennsylvania, have invented certain new and useful Improvements in Railroad-Ties, of which the following is a specification.

My invention relates to railroad cross-ties; and it consists in providing a tie made of cement and covered on its top and sides with sheet metal. Rail-fastening means are also provided consisting of buttons slidably mounted in transverse slots in the tie and a hooked rod secured by means of a nut and 15 having a wide portion adapted to fit between the shanks of the buttons aforesaid and hold them in a securing position.

The details of construction of my invention will be described at length hereinafter and 20 illustrated in the accompanying drawings, in which—

Figure 1 is a top plan view of a railroad-tie constructed in accordance with my invention; Fig. 2, a cross-section of the same; Fig. 25 3, a view showing a top plan view of one end of the tie, on an enlarged scale, partly broken away; Fig. 4, an end view; Fig. 5, a detail view of one of the buttons; Fig. 6, a detail view of the fastening-hook; Fig. 7, a detail 30 view of the clip at each end of the casing; and Fig. 8 a detail view of the nut-locking device.

In the drawings similar reference characters indicate corresponding parts throughout the several views.

35 A represents an inverted casing made of metal inclosing a core of cement or other plastic composition B, the casing A consisting of top a, sides a', and inwardly-extending flanges a'', extending under the core B a short 40 distance, so as to retain it in the casing. The top a is provided near each end with a circular hole C, having slots D extending therefrom toward the sides of the casing and a longitudinal slot E cut into the top a the width of a 45 railroad-rail distant from hole C.

G represents buttons having heads g shaped to clamp one edge of the base of a rail H and having a round shank I adapted to fit into circular holes C and having two sides immediately under the heads g cut away, as shown at i, leaving a narrow web J, adapted to fit in slots D.

The core is cut out, as shown at K, from under the slots E at each end of the casing, 55 and L represents a rod inserted in said cut-

out portion, having a hook M at one end, a wide portion N adjacent to said hook, and its other end provided with screw-threads l.

O represents a dovetail-shaped notch cut into each end of the casing-top a. 60

P represents a clip having a vertical portion p, provided with hole p' to receive the threaded end l of rod L, a horizontal portion Q, and side wings R.

S represents a nut secured on threaded 65 portion l, and T an inverted-U-shaped locking member having beveled sides t to fit the ends of notch O, said locking member engaging the sides of nut S to prevent it from turning. 70

In securing the rail H in position the buttons G are first placed in position by inserting their shanks I in circular hole C and then sliding a button to the extremity of each slot D. The rail is then placed in position, the edge of 75 its base being slid against the button-heads g. The rod L is then inserted in the cut-out portion K of core B, and the hook M, emerging from slot E, clamps the other side of the base of rail H, while the wide portion N, adjacent 80 to the hook M, fits between the sinks I of buttons G and keeps them from movement. The rod L is held in position by means of clip P, through the hole p' of which the threaded end l of said rod is inserted, while nut S 85 serves to tighten the rod and securely clamp the base of the rail between buttons G and hook M. After the nut S is tightened on the rod the locking member T is driven into position and the rail is securely fastened in position. 90

Having thus described my invention, what I claim is—

1. A rail-fastening device for railroad-rails consisting of a cross-tie having a transversely 95 and longitudinally slotted top, buttons to fit in said transverse slots, rods having hooks thereon projecting from said longitudinal slots, and means to secure said buttons and rods in position, substantially as shown and 100 described.

2. A rail-fastening device for railroad-rails comprising a cross-tie having a circular hole adjacent to each end with slots extending therefrom transversely of the tie and slots 105 extending longitudinally of the tie, buttons having round shanks to fit into said circular holes and narrow webs to fit into the slots extending from said circular holes, a rod having a hooked end projecting from each longitudi- 110

dinal slot, and means to secure said buttons and rods in position, substantially as shown and described.

3. A rail-fastening device for railroad-rails comprising a cross-tie having a circular hole adjacent to each end with slots extending therefrom transversely of the tie and slots extending longitudinally of the tie, buttons having round shanks to fit into said circular holes and narrow webs to fit into the slots extending from said circular holes, a rod having a hooked end projecting from each longitudinal slot, a wide portion on each rod to fit between the button-shanks, and means to secure the rods in position, substantially as shown and described.

4. A railroad-tie comprising an inverted casing, a core of plastic material in said casing, the top of said casing provided with circular holes adjacent to each end with slots extending therefrom transversely of the tie and slots extending longitudinally of the tie, the core aforesaid channeled under said top from the longitudinal slots to the ends of the tie, buttons having round shanks to fit into said circular holes and narrow webs to fit into the slots extending from said circular hole transversely of the tie, heads on said buttons to fit the edges of the rail-base, a rod inserted in each channel in said core having a wide portion seated between the shanks on said buttons, a hook on one end of each rod projecting from the longitudinal slot in the tie and clamping the other edge of the base of the rail, a dovetail-shaped notch at each end of the top, a clip secured in said notch having a hole therein to receive the free end of the rod, said free end of the rod threaded, a nut secured on said threads, and an inverted-U-shaped member inserted in said dovetail-shaped notch having beveled sides to fit said notch and engaging the sides of said nut, substantially as shown and described.

nut secured on said threads, and an inverted-U-shaped member inserted in said notch and 40 engaging the sides of the nut, substantially as shown and described.

5. A railroad-tie comprising an inverted casing having inwardly-extending flanges on each base edge, a core of plastic material in 45 said casing, the top of the casing provided with circular holes adjacent to each end with slots extending therefrom transversely of the tie, and slots extending longitudinally of the tie, the core aforesaid channeled under said 50 top from the longitudinal slots to the ends of the tie, buttons having round shanks to fit into said circular holes and narrow webs to fit into the slots extending from said circular holes transversely of the tie, heads on said 55 buttons to fit the edges of the rail-base, a rod inserted in each channel in the core having a wide portion seated between the shanks on said buttons, a hook on one end of each rod projecting from the longitudinal slot in the tie and clamping the other edge of the base of the rail, a dovetail-shaped notch at each end of the top, a clip secured in said notch having a hole therein to receive the free end of the rod, said free end of the rod threaded, a nut 60 secured on said threads, and an inverted-U-shaped member inserted in said dovetail-shaped notch having beveled sides to fit said notch and engaging the sides of said nut, substantially as shown and described.

In testimony whereof I hereto affix my signature in the presence of two witnesses.

GARDNER A. BELKNAP.
